UNITED STATES PATENT OFFICE

NORMAN L. SNOW, OF DETROIT, MICHIGAN, ASSIGNOR TO DIAMOND POWER SPECIALTY CORPORATION, OF DETROIT, MICHIGAN, A CORPORATION OF MICHIGAN

BOILER CLEANER

Application filed June 29, 1925. Serial No. 40,424.

The invention relates to boiler cleaners and has for its object to provide an improved boiler cleaner having a rotary blower nozzle adapted to discharge a cleaning fluid upon the boiler tubes and other parts of the boiler to be cleaned.

Referring to the accompanying drawings in which like reference characters indicate corresponding parts:

10 Figure 1 is an elevational view of one form of my boiler cleaner shown mounted in the boiler wall;

Figure 1^a is a like view of a modified construction of boiler cleaner;

15 Figure 2 is sectional view through 2—2 of Figure 1;

Figure 3 is a view corresponding to Figure 2 showing a modification;

Figure 4 is a like view illustrating a further modified form;

Figure 5 represents a side elevation view of the construction shown in Figure 4;

Figure 6 is a view corresponding to Figure 2 showing a still further modified construction;

Figure 7 is an elevation view partly in section illustrating a modified construction of the sleeve and nozzle arrangement; and

Figure 8 is a sectional view through 8—8 of Figure 7.

Referring to Figure 1, reference character 10 indicates the blower head which may be mounted in an opening 11 extending transversely through the boiler wall 12. 13 is a housing which may be fixed at its forward end to the head 10 so as to form an extension thereof inside the boiler wall 12. 14 is an element movable longitudinally within the housing 13 so as to have a telescopic engagement therewith. Outward movement of the element 14 may be limited by engagement of an annular shoulder 14' of the element 14 with the inwardly extending annular shoulder 16 of the housing 13. The element 14 is preferably non-rotative and is adapted to conduct a suitable cleaning fluid from the supply pipe 17 and head 10, longitudinally of the element 14. Rotatably mounted on the distal end of the element 14 is a sleeve or member 15 provided with one or more cleaning fluid

discharge nozzles 19 positioned to discharge a jet of cleaning fluid tangentially of the element 14. 20 represents the usual boiler tubes.

Referring to Figure 2, the element 14 is provided with a circumferentially extending opening 21 for conducting the cleaning fluid from the element 14 to the discharge nozzles 19. The length of this opening may be varied in accordance with the desired arc of active discharge of the cleaning fluid from the nozzles 19. As shown in Figure 2, it is preferable to extend the opening for at least a semi-circumference so that one of the discharge nozzles will at all times register with the opening 21, where the nozzles are arranged as shown in Figure 2.

Rotation of the sleeve 15 and nozzles 19 will be produced by the reaction of the cleaning fluid discharged from the nozzles. In order to dampen the speed of rotation of the sleeve 15 on the relatively fixed element 14, pins 22 are fixedly mounted on element 14 and are adapted to cooperate with the circumferentially extending notches 23 of the sleeve 15 for producing a shuttling movement of the sleeve.

Secured to the end of the element 14 and extending longitudinally within the same, is a rod 24 having a threaded portion 25 extending through the head 10 for engagement by a wheel 26.

In operation of the boiler cleaner shown in Figures 1 and 2, upon admission of cleaning fluid from the supply pipe 17, element 14 is urged outwardly from housing 13 by the piston action of the cleaning fluid against the end surface 27 of the element 14. Wheel 26 may be manually or otherwise rotated to coact with the threaded portion 25 of the rod 24 to either permit projection or withdraw the element 14 so as to move therewith the sleeve 15 and nozzles 19 to position the latter at a plurality of points for cleaning the boiler tubes 20 and other parts of the boiler. The cleaning fluid conducted along the element 14 passes to the nozzles 19 by reason of the opening 21, the reaction of the jets of cleaning fluid causing rotation of the sleeve 15 in the direction of the arrow shown in Figure 2. As the sleeve rotates the pins

22 will cooperate with the notches 23 to produce a shuttling movement of the sleeve 15 and thereby dampen the speed of rotation of the sleeve to any desired degree. It will be apparent that any number of telescoping sections may be provided to permit extension of the element 14 for any desired distance inside the boiler wall 12. As shown in Figure 2 the opening 21 is preferably of sufficient length to at all times register with one of the nozzles 19. With this arrangement initial rotation of the sleeve 15 is always assured.

15 The boiler cleaner shown in Figure 1^a differs from the construction shown in Figure 1 in that the telescopic feature is omitted. In Figure 1^a the blower head 10^a is provided with a non-rotative fluid conducting element 14^a. At a plurality of desired points longitudinally of this element are positioned sleeves 15^a provided with cleaning fluid discharge nozzles 19^a rotatable with the respective sleeves in the same manner as that shown in Figure 1.

20 Referring to Figure 3, a sleeve 15^b is shown provided with the discharge nozzles 19^b corresponding to the sleeves shown in Figures 1 or 1^a. 14^b is the fluid conducting element about which, the sleeve 15^b is adapted to rotate. The element 14^b is provided with fluid conducting openings 21^b for supplying fluid to the circumferentially extending conduits 28, formed between element 14^b and sleeve 15^b. Projections 29 may be provided inwardly on the sleeve 15^b to hold the sleeve in spaced relation with the relatively fixed element 14^b. In this construction the cleaning fluid passes from the element 14^b through the openings 21^b to the discharge nozzles 19^b by reason of the circumferential conduits 28. With this arrangement an effective blowing arc of 360° may be obtained.

25 In Figures 4 and 5, I have illustrated a modified arrangement for dampening or partially balancing the reactions from the cleaning fluid discharge nozzles. In these figures, 14^c represents the relatively fixed fluid conducting element upon which is rotatably mounted the sleeve 15^c provided with a cleaning fluid discharge nozzle 19^c. Opposite the nozzle 19^c is mounted a smaller nozzle 19^d facing in the same direction as the nozzle 19^c. Thus, the reaction of the cleaning fluid escaping from nozzle 19^d will tend to produce rotation of sleeve 15^c in a direction opposite from that produced by the reaction of the fluid discharged from the larger nozzle 19^c. The reaction of the fluid escaping from nozzle 19^c will cause the sleeve 15^c to rotate in the direction shown by the arrow in Figure 4, the nozzle 19^d serving to only partially counteract the effect of the reaction of the nozzle 19^c so as to permit rotation of the sleeve 15^c at a reduced rate of speed which may be readily regulated by the relative positions or

5 capacities of discharge of the nozzles mounted on the sleeve 15^c. Cleaning fluid is conducted to the nozzles by reason of the openings 21^c and the circumferential conduits 28^c. The element 14^c may be provided with positioning pins 30 for guiding the sleeve 15^c in its rotative movement.

10 Referring to Figure 6, I have provided means for assuring that the discharge nozzle, when the cleaning fluid is turned off the system, will be positioned in registration with the fluid conducting passages so as to always be in position for the next operation of the system. In this figure, the relatively fixed fluid conducting element 14^e is shown mounting the rotatable sleeve 15^e which is provided with the discharge nozzle 19^e. A counterweight 31 of suitable size may be suitably positioned on the sleeve 15^e so as to balance the sleeve in such a manner that when the sleeve is in static equilibrium (when the cleaning fluid is turned off the system,) the inlet to the nozzle 19^e will be located opposite the port 32 which conducts the fluid from the element 14^e to the nozzle. The function of the counterweight 31 during the rotation of the sleeve when the cleaning fluid is being supplied to the nozzle is that of a fly wheel. Thus, the counterweight decreases the rate of acceleration of the sleeve when the cleaning fluid is first introduced into the system, but causes the same to run more smoothly during its rotation. The forces incident to the discharge of the cleaning fluid from the nozzle 19^e tending to produce friction between the sleeve 15^e and the element 14^e, are partially counterbalanced by the centrifugal force of the weight 31 during the rotation of the sleeve.

15 Referring to Figures 7 and 8 the element 14^f is shown mounting the rotatable sleeve 15^f, the latter being provided with a plurality of nozzles 19^f spaced longitudinally of the sleeve and circumferentially thereof with respect to each other so as to position the nozzles at various desired points. The element 14^f may be provided with pins 22^f for cooperation with the notches 23^f to produce a shuttling movement of the sleeve in a manner corresponding with that described in connection with the boiler cleaner shown in Figure 1. The nozzles may be of varying size and varying blowing arc as desired. As shown in Figures 7 and 8, all of the nozzles may be positioned so that the reaction of the cleaning fluid discharged therefrom will tend to produce rotation of the sleeve 15^f in the same direction. Arcuate slots 21^f are provided for conducting the cleaning fluid from the element 14^f to the respective discharge nozzles 19^f. If these slots are all cut on substantially the same arc with the ends of the slots aligned as would be general practice, it is obvious that a suitable number and arrangement of nozzles might be provided so

that one of the nozzles 19^t will be left positioned opposite one of these slots when the supply of cleaning fluid is shut off from the system. Sleeve 15^t will thus be rotated when the cleaning fluid is initially supplied to the element 14^t, by the reaction of the jet from the single nozzle which was left in registration with its port 21^t when the cleaning fluid supply was shut off. With such construction, therefore, it is thus impossible for the sleeve 15^t to be left in a "dead" position. Means is thus provided to insure rotation of the sleeve regardless of the position in which it is left when the supply of cleaning fluid is shut off.

What I claim as my invention is:—

1. In a boiler cleaner, a relatively fixed element, a member rotatable on said element, and provided with a discharge nozzle, means for supplying a cleaning fluid to said nozzle, the nozzle being so arranged that the reaction of the cleaning fluid issuing from the same will impart a rotary movement to the member and means for imparting a shuttling movement to said member upon rotation of the same.

2. In a boiler cleaner, a relatively fixed element, a member rotatable on said element, and provided with a discharge nozzle, the said member having a notched portion, means for supplying a cleaning fluid to said nozzle, the nozzle being so arranged that the reaction of the cleaning fluid issuing from the same will impart a rotary movement to the member, and means acting on the notched portion of said member for effecting a shuttling of said member to oppose the rotation thereof.

3. In a boiler cleaner, a relatively fixed element, a member rotatable on said element, and provided with a discharge nozzle, means for supplying a cleaning fluid to said nozzle, the nozzle being so arranged that the reaction of the cleaning fluid issuing from the same will impart a rotary movement to the member, and means for producing a shuttling movement of said member on the said relatively fixed element for opposing the rotary movement of the member.

4. In a boiler cleaner, a relatively fixed element, a member rotatable on said element and provided with a discharge nozzle, means for supplying a cleaning fluid to said nozzle, the nozzle being so arranged that the reaction of the cleaning fluid issuing from the same will impart a rotary movement to the member, and means for moving the said member and nozzle as a unit in the direction of the length of the element upon rotation of the said member.

5. In a boiler cleaner, a relatively fixed element, a sleeve rotatable on said element and provided with a discharge nozzle, means for supplying a cleaning fluid to said nozzle, the nozzle being so arranged that the reaction

of the cleaning fluid issuing from the same will impart a rotary movement to the sleeve, said sleeve being provided with circumferentially extending notches, and pins carried by the said element engageable with said notches to effect a shuttling movement of the sleeve as the latter rotates.

6. In a boiler cleaner, a relatively fixed element, a member rotatable on said element, the said member being provided with a discharge nozzle and being provided with notched edge portions, means for supplying a cleaning fluid to said nozzle, the nozzle being so arranged that the reaction of the cleaning fluid issuing from the same will impart a rotary movement to the member, and a member carried by said fixed element and engageable with the notched edges of said rotatable member for opposing the rotation of the rotatable member.

7. In a boiler cleaner, a relatively fixed element, a member rotatable on said element and provided with a discharge nozzle, means for supplying a cleaning fluid to said nozzle, the nozzle being so arranged that the reaction of the cleaning fluid issuing from the same will impart a rotary movement to the member, and means for moving the said member and nozzle as a unit in the direction of the length of the element, said last mentioned means including a threaded rod and a wheel threadedly engageable with said rod.

8. In a boiler cleaner, a relatively fixed element, a member rotatable on said element and provided with a pair of discharge nozzles, means for conducting a cleaning fluid to said nozzles, the nozzles being so arranged that the reaction of the cleaning fluid discharged from one of said nozzles will produce rotation of the said member while the reaction of the cleaning fluid discharged from the other of said nozzles will retard the rotation of the said member.

9. In a boiler cleaner, a relatively fixed element, a member rotatable on said element and provided with a pair of discharge nozzles, means for conducting a cleaning fluid to said nozzles, the nozzles being so arranged that the reaction of the cleaning fluid discharged from one of said nozzles will produce rotation of the said member while the reaction of the cleaning fluid discharged from the other of said nozzles will retard the rotation of the said member, the first said nozzle having a greater discharge capacity than the second said nozzle.

10. A boiler cleaner comprising a fluid conducting element provided with an opening, a member rotatable on said element and provided with a discharge nozzle adapted to communicate during portions of the arc of rotation of the said member with said opening, the nozzle being so arranged that the reaction of the cleaning fluid issuing from the same will impart a rotary movement to

the member, and means automatically effective upon shutting off the supply of cleaning fluid to the nozzle for moving the said member into a position establishing communication between the said opening and the nozzle.

11. A boiler cleaner comprising a fluid conducting element provided with an opening, a member rotatable on said element and provided with a discharge nozzle adapted to communicate during portions of the arc of rotation of the said member with said opening, the nozzle being so arranged that the reaction of the cleaning fluid issuing from the same will impart a rotary movement to the member, and a counterweight so proportioned and carried by the member as upon shutting off the supply of cleaning fluid to the nozzle to move the said member into a position establishing communication between the said opening and the nozzle.

12. A boiler cleaner comprising a fluid conducting element provided with an opening, a member rotatable on said element and provided with a discharge nozzle adapted to communicate during portions of the arc of rotation of the said member with said opening, the nozzle being so arranged that the reaction of the cleaning fluid issuing from the same will impart a rotary movement to the member, and a counterweight so proportioned and carried by the member as upon shutting off the supply of cleaning fluid to the nozzle to move the said member into a position establishing communication between the said opening and the nozzle, said counterweight acting upon rotation of the said member to decrease the initial acceleration of the member and to minimize the friction between the member and element produced by the cleaning fluid issuing from the nozzle.

In testimony whereof I affix my signature.
NORMAN L. SNOW.
